ROOF CONSTRUCTION

Herbert A. Faber, Cincinnati, Ohio

Application June 2, 1938, Serial No. 211,341

4 Claims.

(Cl. 108—6)

This invention relates to an improved roof construction for buildings, and finds particular application in flat, load carrying roof structures, such as a sun deck or porch, popular in modern house construction.

The invention contemplates a load carrying sub-structure, preferably concave to form a water gathering surface with which a centrally located down spout may be employed, membrane metallic surfacing material overlying said sub-structure and elastically secured thereto, and a wear-resistant deck or flooring applied directly on said metallic membrane, in conformity with the secondary purpose of the structure as a useful, load-bearing deck.

It is a feature of the invention that the metallic membrane is not rigidly affixed to the supporting structure *per se*, thereby providing for independent movement of the membrane with respect to the sub-structure under varying thermal conditions, and thus eliminating the creation of localized strains within the membrane created by the resistance of the customary rigid securing means to expansion- or contraction-induced movement of the membrane. It is an additional feature that the membrane roof-covering is at all times under a substantially uniform condition of tensile stress.

Other features and advantages will hereinafter appear.

In the accompanying drawing:

Figure 1 is a transverse section taken through a roof structure embodying my invention;

Figure 2 is a sectional detail, particularly illustrating the resilient side support of the metallic membrane surfacing material; and

Figure 3 is a sectional detail showing the construction at the down spout.

Referring to Figure 1, a load-supporting roof-structure 10 is illustrated as having a preferably flat sub-base 11, which may be a concrete slab supported on walls 12, 13 and structurally reinforced by a suitable beam 14. The sub-base 11 is the basic supporting structure of the roof proper, which may include a filling 15 of gypsum-sawdust mixture, cinder concrete, or similar hard-setting, moldable material capable of bonding with the sub-base, and workable into a desired configuration; a metallic membrane water-proof surfacing or pan 16, in contact with the fill 15, but not otherwise affixed thereto; and a wear-resistant flooring or decking, which may be fabricated of ceramic tiles, slates, or concrete blocks 18, laid in an adhesive bonding material, such as a suitable asphaltic mastic layer 20, which

integrates the tiles 18 into a continuous floor surface and adhesively secures them to the roof-pan 16. The pan 16 preferably overhangs the sides of the roof slab 11, see Figure 2, and at such overhanging sides, there is provided a resilient spring member 21 suitably anchored to the slab 11 and engaging the edges of the membrane, as shown.

Advantageously, the fill 15 is concave, providing for the drainage of water to a central point 10 at which a tile 18a, provided with an opening in register with a suitable down spout 22, accommodates the removal of water from the roof.

The metallic pan 16 is preferably fabricated of sheets of copper or foil thickness. Overlapping 15 joints between contiguous sheets are advantageously soldered, to form an integral, water-tight unit, coextensive with the roof structure. A suitable collar or flange 23 may be provided at the down spout 22, to make a water-tight connection 20 therewith.

Provision is made for the expansion- or contraction-induced movement or creepage of the roof-pan 16 in any degree, said provision incidentally maintaining the pan under uniform conditions of tensile stress. The overhanging marginal surfaces of the metallic roofing may be reinforced, as by a rigid strip 24, see Figure 2, soldered or otherwise secured to the roof pan. The metallic roofing, which rests upon the fill 15 but is preferably not secured thereto, is resiliently anchored to sub-base 11 by the cooperating spring members 21, see Figs. 1 and 2. The members 21 may be of spring brass or phosphor bronze, having a leg or base 21a interposed between the fill 15 and sub-base 11 and rigidly secured to the latter, and an outwardly reaching edge 21b, arranged to engage a hook or channel 24a formed by inwardly folding the reinforcing strip 24. The members 21 are at all times under 30 spring tension, and maintain the metallic membrane covering 16 under continual tensile stress.

The members 21 are preferably coextensive with the edges of the roof structure and, therefore, prevent rain or moisture from being driven 45 into the fill 15, or between the pan 16 and the fill; and additionally form a wind break which is effective to minimize exertion of wind-pressure stresses under the overhanging edges of pan 16.

The tiles 18 provide the necessary abrasion- 50 protection to the copper foil, in conformity with the secondary purpose of the roof structure as a load-bearing deck. Additionally and incidentally, the tiles serve to maintain the copper foil pan-structure in intimate surface contact 55

with the fill 15, thereby supplementing the tension-inducing members 21 in maintaining the copper membrane in smooth, non-buckling relationship with the fill 15.

- 5 5 In the described structure, it will be evident that the various components may have respectively different coefficients of expansion. As respects the roof sub-structure per se, the copper is free to expand or contract, and, because of the 10 uniform tension maintained in the copper by the members 21, is not subjected to localized strains. The elasticity inherent in the asphaltic mastic layer 20 accommodates the relative difference in the expansion coefficient of the 15 mastic and the copper, without inducing rupturing strains in the copper pan, both being capable of relative movement under different thermal expansion or contraction without separation.
- 15 20 Whereas I have described my invention by reference to specific forms thereof, it will be understood that many changes and modifications may be made without departing from the spirit of the invention.

25 I claim:

1. A roof covering for a building, comprising membrane waterproofing material laid upon said roof and displaceable with respect thereto, wear resistant material superimposed upon said 30 membrane, and continuous imperforate spring means substantially coextensive with the marginal edges of said membrane material secured to said building at a point substantially below the point of contact of said membrane material 35 with said roof and in operative association with said membrane material to exert a tensile pull upon said membrane waterproofing material, upon said imperforate spring means forming a flash-

ing for preventing an ingress of water between the said membrane waterproofing material and said roof.

2. A roof covering for a building, comprising membrane waterproofing material laid upon said roof and displaceable with respect thereto, and spring means secured to said building beneath the said membrane waterproofing material and within the periphery of said membrane waterproofing material and operatively associated with 10 said material to place the same under tensile stress.

3. A covering for the roof of a building and means for securing said roof covering, comprising the combination with membrane waterproofing material laid upon said roof and projecting beyond the marginal edges thereof, of spring means secured to said building substantially beneath said membrane layer and extending upwardly and outwardly from said building 20 to a point of engagement with said membrane layer, said spring means being adapted to place said membrane layer under tension.

4. A covering for the roof of a building and means for securing said roof covering, comprising the combination with sheet waterproofing material laid upon said roof and extending beyond the marginal edges thereof, said sheet waterproofing material being provided with reinforced edge portions embodying channel means 30 disposed on the under side of said sheet waterproofing material, of spring means secured to said building beneath said sheet material and extending outwardly to engage said channel means, said spring means being adapted to subject said sheet 35 material to tensile stress.

HERBERT A. FABER.
